UNITED STATES PATENT OFFICE

2,058,254

HEATING APPLIANCE

Paul C. Pederson, Duluth, Minn.

Application September 10, 1934, Serial No. 743,386

3 Claims. (Cl. 126—67)

This invention relates to heating appliances, such as stoves or furnaces, and the principal object is to produce a more efficient unit of this type than heretofore known, and one in which air is circulated by force in conjunction therewith.

Other objects and advantages of the novel structure will appear from the following description thereof.

Referring now to the accompanying drawing, forming part of this application, and wherein like reference characters indicate like parts:

Figure 1 is a central vertical section through a stove embodying the invention.

Figure 2 is a reduced top view of the fire box section of the stove.

Figure 3 is a top plan view of the stove, illustrating the smoke flue.

The body portion of the stove is preferably made of three separable sections, 1, 2 and 3 indicating the base portion, while 4 represents the fire pot section and 5 the top section or combustion chamber. 6 represents the outer casing or jacket which rests upon the portion 1 of the base.

The base portion 1—2—3 is somewhat pyramidal in form, in that it tapers upwardly from all sides, being preferably circular in shape, that portion surrounded by the section 1 forming an inlet air chamber, the walls of which are provided with any desired number and form of openings as illustrated at 7. Above this section the portion is somewhat smaller in diameter forming a stepped annular ledge which functions conveniently in receiving the jacket 6.

Within the chamber formed by the section 2 is installed the fan 8 and the electric motor 9 which is supported as by a spider 10 intermediate of the two sections 1 and 2. The section 3 is still smaller in diameter, the surface of which is inclined materially toward a circular central opening for the reception of the smaller end of the section 4 of the stove and is spider like in form for the reception of the lower ends of the radiating fins 14 so that air is freely forced through the section 3 intermediate of said fins. The section 4 is of inverted truncated cone shape with the smaller lower end 14 extending downwardly within the base portion in fairly close proximity to the fan, and this portion functions as an ash pit, or for the reception of and removal of an ash pan as indicated at 12. The grates of the stove occur as shown at 13 at approximately the junction of the section 4 of the body of the stove and the base thereof, and this section 4 is illustrated as having one of its radiating fins 14 omitted, providing room for the door 21, damper 22, and

other necessary accessories for manipulation of the stove. The portions 4 and 5 of the body are of similar construction, that is being designed to rest one upon the other with their larger diameters registering and their smaller ends farther apart, and they are further alike in that both are equipped with registering radially extending heat conducting vanes or fins 14, these being somewhat V-shaped in cross-section and extending well out towards the jacket. The jacket is also smallest at its two ends and of larger diameter transverse its central portion to somewhat coincide with the shape of the body of the stove. These vanes or radiating fins 14 are equi-distant, and vertically disposed with the exception of the one in the front of the stove which is omitted to provide convenient room for access to the interior of the stove, or to doors and the like.

In this manner a plurality of air conduits or channels indicated at 15 are formed wholly about the body of the stove and when the fan 8 is rotated by operation of the motor 9 air is driven upwardly through these channels and out the upper open end of the jacket 6 which is found to greatly augment the distribution of the heat units from the stove into the atmosphere above and about the stove.

A further novel feature of the invention is the disposition of the gases and smoke above the combustion chamber, and is accomplished by forming the wall 16 transverse the upper end of this chamber and spaced from the top thereof, providing the annular ring like chamber 17 intermediate the top of the section 5 and the wall 16, said latter wall being provided with the circular central opening 18 which communicates through the damper controlled opening 19 with the circular chamber 17, the opposite or exhaust end of the chamber 17 communicating with the pipe thimble or collar 20. A partition or deflector 23 is interposed in the annular chamber 17 at one edge of the opening 19. This partition may be swingable to constitute a form of damper if desired. The partition 23 assists in directing the air from the central opening 18 into the annular chamber 17. It is apparent that the damper 22 may be controlled in any desired manner for regulating the draft of the stove. Damper 22 in the form shown is provided with apertures adapted to register with apertures in the fire pot and by shifting registration of the two sets of apertures the draft through this damper may be controlled.

As additional draft control means apart from the damper 22 above referred to, I have illustrated an annular damper ring 24 about the

upper end of the lower portion 11 of the section 4, and this damper ring is perforated and designed to control, by rotation thereof, a series of holes indicated at 25 about said portion 11. 5 For control of this damper ring I have illustrated the thumb button 26, similar to the button 21 on the damper 22. By this means it is evident that forced draft facilities may be employed at will as, when the fan 8 is rotated and the 10 damper 24 opened, forced draft will occur within the stove.

Having thus described my invention, what I claim and desire to secure by Letters Patent, is:

1. A heater of the type described comprising 15 a hollow metal base the lower portion of which freely communicates with the surrounding atmosphere, a motor driven fan installed axially within said base, a fire box section and a combustion chamber section superposed upon each other and 20 upon said base, integrally formed radiating fins projecting laterally from said fire box section and combustion chamber section and extending longitudinally for substantially the full height of said sections, and a casing about said fins, 25 said fire box section characterized by being of inverted frustro conical shape to insure maximum circulation of air from said motor fan, said fins traversing substantially the space between said casing and said fire box and combustion chamber 30 sections.

2. A heating unit comprising a vertical casing having an open lower end and provided with an air discharge at its upper end, a base upon which

said casing is mounted, said base having air intake passages in the lower portion thereof, a fire box section and a combustion chamber section superimposed upon each other and having closed lower and upper ends respectively and mounted in spaced relation to said casing, said fire box section being mounted some distance above the bottom of said base, said fire box and combustion chamber sections having continuous radiating fins extending substantially the combined full 13 heights of said sections and substantially traversing the space between said sections and said casing, the upper portion of the interior of said base constituting a fan housing for directing air 15 upwardly between said fins and against the peripheral walls of said sections, a fan mounted axially on said housing, walls within the upper portion of said combustion chamber defining a passageway communicating with the upper end of said combustion chamber and extending circumferentially thereof for retarding the discharge 20 of the hot products of combustion and for increasing the amount of heat radiated at the top of said fins, and a flue connected with said passageway.

3. The structure set forth in claim 2 wherein 25 said walls define a concentric annular passageway in the top of said combustion chamber and a flue disposed eccentrically of said passageway and communicating therewith for the disposition 30 of smoke and gases.

PAUL C. PEDERSON.
